UNITED STATES PATENT OFFICE.

GEORGE W. PROUTY, OF DORCHESTER, MASSACHUSETTS.

HOLDER FOR SALES-CHECKS.

1,130,629.

Specification of Letters Patent.

Patented Mar. 2, 1915.

Application filed November 15, 1913. Serial No. 801,303.

To all whom it may concern:

Be it known that I, GEORGE W. PROUTY, a citizen of the United States of America, and a resident of Dorchester, in the county 5 of Suffolk and State of Massachusetts, have invented certain new and useful Improvements in Holders for Sales-Checks, of which the following is a specification.

This invention relates to holders for sales- 10 checks, and has for its object the provision of a device of this class in which the sales- checks may be retained conveniently and in which when the checks have been used the stubs thereof may be removed quickly there- 15 from to permit the insertion of a new set of sales-checks.

The invention consists in a boxlike frame open at one side and one end and having rev- 20 olubly mounted therein a threaded spindle, one end of which is provided with means outside the box for rotating said spindle, while the opposite end is normally locked by a pivoted cover to prevent the removal of 25 the checks from said spindle, said checks being forced against said cover by means of a nut threaded to said spindle.

The invention further consists in certain 30 novel features of construction and arrangement of parts which will be fully understood by reference to the description of the drawings and to the claims hereinafter given.

Of the drawings: Figure 1 represents a 35 plan of a device embodying the principles of the present invention. Fig. 2 represents a vertical section of the same, the cutting plane being on line 2—2 on Fig. 1, and Fig. 3 represents a transverse vertical section of the same, the cutting plane being on line 3—3 on Fig. 2.

Similar characters designate like parts 40 throughout the several figures of the drawings.

In the drawings, 10 is a boxlike frame having an open side 11 and an open end 12 45 as indicated in Fig. 2 of the drawings. This boxlike frame 10 may be made up in any preferred manner. It is provided on one side with a clip 13 pivoted at 14 and having secured to its inner face a toothed mem- 50 ber 15 which is adapted to grip upon the belt of the person using the sales-checks, force being applied for this purpose to the clip by the spring 16 coiled about the pivot 14. The bottom 17 of the box 10 is pro- 55 vided with a cylindrical opening in which is positioned the reduced end 18 of a thread-

ed spindle 19 extending lengthwise of said box frame 10. That portion of the reduced end 18 extending beyond the lower face of the bottom 17 has secured thereto the milled head or collar 20 by which the threaded spindle 19 may be rotated. Between the threaded body portion of the spindle 19 and the inner face of the bottom 17 is inter- 60 posed a washer 21. Mounted upon and threaded to the spindle 19 is a nut 22 hav- 65 ing flanges forming a part thereof to which is riveted the bottom plate 23 extending out- 70 wardly from the open end 11 of the box frame 10 and adapted to support the set of 75 sales checks 24 contained within the holder. The stub ends 25 of the sales checks 24 are provided with aligned openings 26 through 80 which the spindle 19 extends, as shown in Fig. 2 of the drawings. The open end 12 of 85 the box frame 10 is provided with a cover 27 pivoted at 28 and is provided with a locking bolt 29 adapted to be operated by a key inserted in the keyhole 30 to move the bolt outwardly through an opening 31 90 in the outer wall 32 of the box frame 10. When the bolt 29 is thus inserted in the opening 31 in the outer wall 32 the cover is locked from movement about its pivot 28. The cover 27 is provided with an extension 95 33 fitting over the upper edge of the outer wall 32 and bearing against its outer face when in normal locked position. This ex- 100 tension 33 forms a stiffening member which prevents the wall 32 from being forced out- 105 wardly and disengaged from the bolt 29. To the under face of the cover 27 is secured a spring plate 34 provided with an opening 35 therethrough through which ex- 110 tends the upper end of the threaded spin- dle 19.

It is obvious from an inspection of Fig. 2 of the drawings that when the cover is in its normal locked position as indicated in said figure, it will be impossible to remove the stubs 25 from the said spindle until the cover has again been unlocked and moved about its pivot 28. When this has been accomplished the stubs of the sales checks may be removed and a new set of sales-checks inserted in the box upon the spindle 19. A spring plate 34 tends to force the stubs downwardly and by turning the milled head or collar 20 the nut 22 with its movable bottom plate 23 may be moved upwardly to firmly clamp the sales checks between the cover and said bottom plate. As the lock-

ing device of the cover 27 forms no part of the present invention it is neither shown nor described in detail, as any well-known form of locking device may be utilized. This 5 forms a very simple yet effective holder for sales checks, the cost of production of which is reduced to a minimum.

It is believed that the many advantages of the invention will be fully apparent from 10 the foregoing description.

Having thus described my invention, I claim:

- 15 1. A device of the class described comprising a boxlike frame having an open side and end; a threaded sales-check retaining spindle supported in the closed end of said box and extending lengthwise thereof through openings in said checks; a cover hinged to the open end of said frame adapted to be locked over the end of said spindle; and a nut movable lengthwise of said spindle beneath the sales checks and adapted to clamp said checks against the inner face of said hinged cover.
- 25 2. A device of the class described comprising a boxlike frame having an open side and end; a threaded sales-check retaining spindle supported in the closed end of said box and extending lengthwise thereof through openings in said checks; a cover hinged to the open end of said frame and adapted to be locked thereto, said cover being provided with an opening therein adapted when locked to receive the end of 30 said spindle; and a nut movable lengthwise of said spindle beneath the sales checks and adapted to clamp said checks against the inner face of said cover and provided with a bottom plate adapted to support the checks 35 and extending to the outer ends thereof.

3. A device of the class described comprising a boxlike frame having an open side and end; a revoluble threaded sales-check retaining spindle supported in the closed end of said box and extending lengthwise 45 thereof through openings in said checks; a cover hinged to the open end of said frame adapted to be locked over the end of said spindle; and a nut threaded to the spindle beneath the sales checks and adapted to be 50 moved lengthwise thereof to clamp the sales checks against the inner face of the locked cover.

4. A device of the class described comprising a boxlike frame having an open side and end; a threaded sales-check retaining spindle extending lengthwise of said box; a cover hinged to the open end of said box and provided with a spring extension having an opening therein through which the end of 55 said spindle is adapted to extend; a nut on said spindle adapted to bear against said sales checks; and means beneath the box for rotating said spindle.

5. A device of the class described, comprising a boxlike frame having an open side and end; a threaded sales-check retaining spindle extending lengthwise of said box; a cover for the open end of said box adapted to be locked over the end of said spindle and 60 to be removed therefrom; and a nut movable lengthwise of said spindle adapted to clamp 65 said checks.

Signed by me at 4 Post Office Sq., Boston, Mass., this 10th day of November, 1913.

GEORGE W. PROUTY.
